UNITED STATES PATENT OFFICE.

ROBERT L. DORAN, OF CHICAGO, ILLINOIS, ASSIGNOR OF THREE-FOURTHS
TO JAMES S. KNIGHT AND J. H. TALBOT MARTIN, OF CHICAGO, ILLINOIS;
AND MATTHEW C. MCGANNON, OF NASHVILLE, TENNESSEE.

DESIGN FOR A GAS-LAMP.

SPECIFICATION forming part of Design No. 35,788, dated March 4, 1902.

Application filed January 30, 1902. Serial No. 91,946. Term of patent 7 years.

To all whom it may concern:

Be it known that I, ROBERT L. DORAN, a citizen of the United States, residing at the city of Chicago, in the county of Cook and State of Illinois, have invented and produced 5 a new and original Design for a Gas-Lamp, of which the following is a specification, reference being had to the accompanying drawing, forming a part thereof.

10 The drawing shows a side elevation of a gas-lamp embodying my design.

The leading or material features of my design consist of a translucent glass globular body surmounted by a canopy, upon which 15 rests an ornamental crown or band, through the center of which extends upwardly a pipe.

In the accompanying drawing, A designates the translucent globular body. B denotes a

concavo-convex disk or canopy of the usual circular form at the top of said body A. 20

C designates an ornamental band resting upon the canopy B at the center. Centrally through the band C extends the gas-pipe D, the lower end of which will carry the cluster of gas-burners. 25

Adjacent the pointed lower end of the globular body A are the openings a.

Having thus described my invention, what I claim as new, and desire to secure by Letters Patent, is—

30 The design for a gas-lamp as herein shown and described.

ROBERT L. DORAN.
